UNITED STATES PATENT OFFICE.

JAMES E. ELLISON, OF SCIOTOVILLE, OHIO.

IRONING-BOARD.

SPECIFICATION forming part of Letters Patent No. 259,118, dated June 6, 1882.

Application filed September 10, 1881. (Model.)

To all whom it may concern:

Be it known that I, JAMES E. ELLISON, a citizen of the United States, and a resident of Sciotoville, in the county of Scioto and State of Ohio, 5 have invented a new and valuable Improvement in Ironing-Boards; and I do hereby declare that the following is a full, clear, and exact description of the construction and operation of the same, reference being had to the 10 annexed drawings, making a part of this specification, and to the letters and figures of reference marked thereon.

Figure 1 of the drawings is a representation of a side elevation of my invention. Fig. 2 is 15 a plan view. Fig. 3 is a bottom view of a portion of the board.

This invention has relation to combined ironing and pressing boards; and it consists in the novel construction and arrangement of parts, 20 as will be hereinafter fully described, and particularly pointed out in the claim.

Referring by letter to the accompanying drawings, A designates an ironing-board, upon which shirts and other garments may be conveniently ironed. This board A is preferably 25 about sixteen inches wide at the end which is to be connected to the table, window-sill, or other support, and tapers to the point to a width of about twelve inches, and should be 30 about four and a half feet in length, as I find this to be the most convenient size for easy manipulation. A slot, B, is provided at the wider end, and a lateral groove, C, traverses the upper face of the board A, as shown in 35 Fig. 1, quite near this wide end, and is intended to engage the table or other support when the device is in use. At the termination of the slot B, and on the under face of the board A, I secure a transverse strengthening - piece, I, 40 which prevents the board A from splitting, and also serves as a base for the attachment of one leaf of a strap-hinge, J, the other leaf of the hinge being secured to the under side of the pressing-board K, which also serves as a 45 brace for the ironing-board A when attached to the table or other support. The pressing-board K tapers to a rounded point, as shown, and has on the under side, at its larger end, a transverse strip, L, to make the bite or clamp- 50 ing-power of the device more certain when attached to its support. The upper end of the

brace or pressing-board K is beveled, as shown, so that when the device is in use as an ironing-board this beveled end will bear on the table. This beveled end has a sad-iron stand, 55 M, on which to rest the sad-iron when not in use.

Attached to the under face of the pressing-board K, near its point, is a spring - brace, N, secured by a screw, N', passed through an eye 60 in the spring portion of the brace, so that the arm portion P may be bent down or turned out of the way of the garment as the latter is being slipped upon the ironing-board A. The arm P of the spring - brace N extends up to 65 within an inch or an inch and a half of the under face of the ironing-board A, and when heavy pressing is to be done the board A will be stopped by the spring-brace N in its downward course, and thus relieve the hinge from 70 the strain that would otherwise come upon it.

As a modification of the spring - brace N, I may employ a swinging brace, Q, which I suspend from the under face of the ironing-board A by a staple or swivel, R. This swinging 75 brace Q is provided at its lower end with a spiral spring, S, the foot of which engages either one of a series of steps or depressions in the face of the pressing-board K to support the ironing - board A under heavy pressure. 80 The shirt is to be slipped upon the point of the ironing-board and then drawn down until the point enters the shoulders and neck of the same. The bosom and a portion of the neck band may then be ironed, and when completed 85 the other portions may be ironed by turning the garment upon the board in a manner that will readily suggest itself.

When the device is used as a pressing-board the ironing-board is converted into the brace 90 and the brace N occupies the position the ironing-board formerly did, as shown in the drawings.

The bosom - board attachments shown connected to the ironing-board form no part of 95 the invention claimed in this application; but the right to make a separate application therefor is hereby expressly reserved.

Having thus fully described my invention, what I claim as new, and desire to secure by 100 Letters Patent, is—

In a combined ironing and pressing board,

the combination, with the board A, slotted at B, and the hinged pressing-board or brace K, of the spring-brace N, secured to the pressing-board K, and having its arm portion P extending to near the ironing-board A, substantially as and for the purposes specified.

5 In testimony that I claim the above I have

hereunto subscribed my name in the presence of two witnesses.

JAMES E. ELLISON.
